PARTITIONED FOLDED-BLANK BOTTLE CARRIER

Walter C. George, St. Louis, Mo., assignor to Gaylord Container Corporation, St. Louis, Mo., a corporation of Maryland

Application September 23, 1949, Serial No. 117,442

2 Claims. (Cl. 229—28)

1

This invention relates to folded-blank paperboard bottle carriers of the kind that are provided with a bottle partition having a handle portion adapted to extend above the tops of the bottles in said carrier.

The principal object of the invention is to provide a bottle carrier of the above type having a fixed partition with a handle portion which normally extends above the tops of the bottles in the carrier and is yieldable downwardly under the pressure exerted thereon by another carrier seated on the tops of the bottles in the lower carrier and tends to return to its normal position when the upper carrier is removed. Other objects are to provide a reusable folded-blank bottle carrier of strong and durable, simple and economical construction which can be shipped in flat knockdown sections adapted for quick and easy permanent assembly by the bottler.

The invention consists in a folded-blank paperboard bottle carrier comprising a permanently open box section, a transverse partition section and a combination longitudinal partition and handle section whose lower portion is disposed in and permanently and immovably secured to said box section and whose handle portion normally extends above the level of the tops of the bottles in the carrier and is yieldable downwardly under vertical pressure thereon to bring the top of the handle portion flush with the tops of the bottles in said box section. The invention also consists in the bottle carrier and in the parts and arrangements and combinations of parts hereinafter described and claimed.

In the accompanying drawings, which form part of this specification and wherein like symbols refer to like parts wherever they occur,

Fig. 1 is a perspective view of a partitioned folded-blank bottle carrier embodying my invention.

Fig. 2 is a perspective view, showing the three sections of the carrier in position for assembly.

Fig. 3 is an end elevational view of the carrier, a portion of the end wall flap being shown broken away.

Fig. 4 is an end elevational view of the carrier, showing the handle portion of the longitudinal portion depressed; and

Fig. 5 is a vertical longitudinal sectional view on the line 5—5 in Fig. 3.

In the accompanying drawings my invention is shown embodied in a folded-blank paperboard bottle carrier comprising a permanently open box section A, a transverse partition section B and a combination longitudinal partition and carrying handle section C.

2

The open box section A of the bottle carrier comprises a bottom panel 1 having upwardly folded end wall panels 2 terminating in upper marginal flaps 3, and side wall panels 4 having folded upper marginal flaps 4a adhesively or otherwise permanently secured to their inner faces and having overlapped inturned end wall flaps with interlocked locking tongues 6. The end wall panels 2 entirely cover the outer faces of the overlapped and interlocked end wall flaps 5.

The transverse partition section B of the carrier is in the form of a relatively deep open-ended channel having a bottom panel 7 with upstanding partition panels 8 along the longitudinal edges thereof. The transverse partition B extends from side to side of the box section A midway of the ends thereof with its bottom panel 7 seated on the bottom panel 1 of said box section and with its upstanding partition panels 8 disposed crosswise of the latter flush with the upper edges thereof. As shown on the drawings, the two transverse partition panels 8 are each provided midway of the side wall panels 4 of the box section A with relatively deep V-shaped notches 9 that extend downwardly from the upper edges of said transverse partition panels to a point substantially midway of the height thereof.

The combination longitudinal partition and handle member C of the carrier comprises two contacting longitudinal partition panels 10 that extend from end to end of the box section A midway of the side wall panels 4 thereof and have reversely extending right angularly disposed end flanges 11 that extend from top to bottom of said box section. The upper marginal flaps 3 of the end wall panels 2 of the box section A are folded over the tops and against the inner faces of the end flanges 11 of the section C on opposite sides of the longitudinal partition panels 10 thereof. The flaps 3, end flanges 11, interlocked end wall flaps 5 and end wall panels 2 are all permanently secured together at the ends of the carrier preferably by means of staples 12. The two flatwise contacting longitudinal partition panels 10 are provided opposite the two cross-partition panels 8 with relatively deep registering inverted V-shaped notches 13 which extend upwardly from the lower edges of said longitudinal partition panels and cooperate with the upwardly opening notches 9 in said cross-partition panels to form an interlocking connection therewith which serves to prevent relative sideways movement of said longitudinal and cross-partition panels.

As shown in the drawings, the two longitudinal partition panels 10 are extended, as at 10^a, above the level of the top of the box section A of the carrier to a point normally disposed above the level of the tops of the bottles located in the compartments formed by said longitudinal panels and the transverse partition panels 8 where the two longitudinal partition panels are integrally connected along the upper edges thereof by a longitudinal fold 14. The handle portions 10^a of the two longitudinal partition panels 10 are also provided with registering hand holes 15; and said hand holes may also be provided along their upper edges with flaps 16 adapted to be bent inwardly through said hand holes to provide a smooth round surface for the fingers.

By the arrangement described, the ends of the lower box section engaging portions of the two central longitudinal partition panels 10 are rigidly secured to the ends of the box and are thus held against vertical and horizontal movement relative thereto, the fixed lower portion of the two longitudinal partition panels serving also to hold the transverse partition section B in proper position in the box section. The securing means for the longitudinal partition and handle section C also serves to secure the elements of the box section A in assembled relation, thereby providing a strong and durable reusable carrier. The upwardly extending handle forming portions 10^a of the two longitudinal partition panels 10 normally extend upwardly in substantially flatwise contact to a point located above the level of the tops of the bottles supported in the carrier so as to provide ample room for inserting the hand between the rows of bottles on the opposite sides of said handle portions and for insertion of fingers in the registering hand holes 15 therein. The upwardly extending handle forming portions 10^a of the two longitudinal partition panels 10 are connected and strengthened by the fold 14 along the upper edges thereof. However, when the carriers are stacked one upon another with the bottom of one carrier seated on the tops of the bottles in the carrier immediately therebelow, the upper carrier presses downwardly against the longitudinal connecting fold 14 along the upper edges of the handle portions 10^a of the two longitudinal partitions 10, thereby spreading said handle portions apart and permitting them to be depressed along their upper edges far enough to enable the upper carrier to seat on the bottles in the lower carrier. When the handle portions 10^a are depressed, they bow outwardly away from each other far enough to permit the required downward movement of the integrally connected upper edges thereof. The depressed handle portions, however, due to the inherent resiliency thereof, tend to spring upwardly into their normal fully extended position when the downward pressure thereon is released.

What I claim is:

1. A bottle carrier comprising an open folded-blank box section having side walls with upper marginal flaps that are permanently secured flatwise to the inner faces thereof and end wall flaps that are folded into overlapped and interlocked engagement and a bottom panel having end wall panels that are folded upwardly against the outer faces of said end wall flaps, a transverse partition member disposed within and extending transversely of said box section with its upper edge

flush with the upper edges thereof, and a longitudinal partition section having a lower portion disposed within said box section in interlocking engagement with said transverse partition section and a handle portion extending above said box section, said lower portion of said longitudinal partition section having end flanges that extend from top to bottom of said box section and seat flatwise against the inner faces of the overlapped and interlocked end wall flaps thereof, said end wall panels having upper marginal flaps thereon that are folded over the upper edges of said end wall flaps and end flanges and are secured thereto, said box section being adapted to hold bottles, said longitudinal partition comprising two side panels that are connected together along the upper edge of said handle portion and are adapted to bow outwardly from each other, said handle portion normally extending above the level of the bottles and being yieldable under downward pressure.

2. A bottle carrier comprising an open folded-blank box having a bottom panel structure, a pair of oppositely disposed side walls and a pair of oppositely disposed end walls forming a box section, a separate partition member consisting of connected together panels substantially co-extensive in dimensions with each other and having the lower portion thereof disposed within said box section and with a handle portion thereof extending above the box section, said lower portion of said partition having end flanges extending vertically and substantially at opposite right angles from each end of each partition panel thereof and constituting two pairs of such flanges that extend over the inner faces of said pair of end walls, said pair of end walls each having an upper marginal flap extension for substantially its full width and the distance between the other of said opposed walls, each flap having an open-ended straight slot therein substantially intermediate of its ends extending at substantially right angles to its inner edge and folded downwardly over the flanges of the partition and fixed to its respective end wall so as to be substantially parallel with the inner face of said wall, and with opposite edges thereof formed by the slot engaging adjacent substantially vertically disposed opposite portions of each panel forming the partition member, whereby the partition member is fixed in the box section against vertical and lateral movements relative thereto.

WALTER C. GEORGE.
